UNITED STATES PATENT OFFICE.

WILLIAM R. COPPAGE, OF WASHINGTON, DISTRICT OF COLUMBIA.

APPARATUS FOR RECEIVING MAIL FROM AND DELIVERING IT TO AEROPLANES WHILE IN FLIGHT.

Application filed November 2, 1918. Serial No. 260,850.

To all whom it may concern:

Be it known that I, WILLIAM R. COPPAGE, a citizen of the United States, and a resident of Washington, District of Columbia, have 5 invented certain new and useful Improvements in Apparatus for Receiving Mail from and Delivering It to Aeroplanes While in Flight; and I do hereby declare the following to be a full, clear, and exact description of the invention, such as will enable others skilled in the art to which it appertains to make and use the same.

My invention relates to an improvement in apparatus for receiving mail from and 15 delivering it to aeroplanes while in flight, and it consists in the parts and combination of parts and in the details of construction as will be more fully explained and pointed out in the claims.

20 In the accompanying drawings; Figure 1 is a view in side elevation partly in section showing my improved apparatus in position to receive and deliver mail; Figure 2 is a view showing the apparatus collapsed 25 or folded, parts being in section; Figure 3 is a plan view of the parts as shown in Figure 1; Figure 4 is a view of a detail and Figure 5 is a view in section showing the means for suspending and releasing a mail 30 bag.

1 represents a frame which may be specially prepared to receive my apparatus, or it may be a building specially constructed or redesigned to receive the apparatus which 35 must be sufficiently high above adjacent objects to provide for safe aeroplane travel. The top of the frame or building 1 carries the bearing 2 through which the mast 3 passes, the bearing 2 being provided with 40 a flange for its attachment to the frame and counterbored to form a runway for the anti-friction balls 4 on which the lower end of the sleeve 5 rests and turns. The mast 3 passes through the sleeve 5 and bearing 45 2, and is provided with an elongated slot 6, in which the inner end of the pin 7, carried by the upper end of the sleeve, rests to lock the sleeve and mast against independent turning movement, the mast 50 however being free to move vertically in the sleeve.

The sleeve 5 is provided with an integral or rigid worm wheel 8 which meshes with the worm 9 for turning the sleeve and the 55 mast so as to properly present the apparatus

to an approaching aeroplane, and the mast is provided at its lower end with a sheave block 10, the sheaves of which are engaged by the rope 11 employed for raising and lowering the mast. One end of the rope 11 60 is made fast at 12 and passes down under one sheave of block 10; up over sheave 13, down under the second sheave on block 10 and up to the drum 14 which may be actuated by hand power or motor as preferred. 65

With the construction thus far described it will be seen that the mast is supported on and carried by the block 10 to which it is swiveled and is sustained laterally by the bearing 2 and thimble 5, and is turned in 70 its bearing and on the sheave block by the sleeve 5.

Journalled in the elbow 3^a at the upper end of the mast 3 is the V-shaped yoke 15, and pivotally secured to the free ends of the two side members of the yoke is the V-shaped guiding frame 16, which is connected to the yoke near its wider end. The sides of this guiding frame come together at their front ends and are pivotally connected at 75 said front end to the upper end of the jointed brace rod 17. The guiding frame 16 may be of wood or light metal and is constructed to present free unobstructed side surfaces against which a rope or cable 80 depending from an aeroplane, can slide or pass over it without meeting any obstructions. This brace rod 17 is provided with a rule joint 18, and is pivotally connected at 85 19 to the platform 20, which is secured by brace 21 to the mast 3 and loosely rests on the top of the turn table 22. This platform 90 20 has an opening for the passage of the mast 3, and the turn table on which the platform is loosely supported, is mounted to 95 turn on the bearing 23 secured to the mast 3, rollers 24^a being interposed between the turn table and bearing to lessen the friction.

The turn table 22 has a peripheral flange 100 22^a which overhangs the bearing 23, and to which are secured the mail bag detaching arms 24. These arms project forwardly and diagonally outwardly forming a V which is reversely placed to that of the guiding frame 16, and which projects outwardly beyond the vertical plane of the side members of said guiding frame, as shown in Figure 3. Each arm 24 is provided with a series of curved slots 25, the front of which are restricted 105 110

and rounded as shown in Figure 3, so that a rope or small cable 26 engaging the front edge of either detaching arm will be guided into one of the slots as the aeroplane flies 5 over the same with the mail bag suspended as shown in Figure 1. The two arms 24 are rigidly secured to the turn table 22, hence when either arm is struck or engaged by the bag carrying cable 26, the contact of the 10 cable against the arm will swing the latter rearwardly, and turn the table 22 and the receiving baskets 28 carried by the turn table in the direction of movement of the mail bag to be discharged. These baskets are 15 preferably shaped as shown and are located at opposite sides of the mast, one at the rear of each arm 24, and in a position to receive the bag to be discharged, and each is composed of a flexible body, preferably of netting, and 20 a rigid, preferably sheet metal, bottom 28a, the latter operating to hold the basket open. These baskets are supported at the top by the arms 29 secured to the turn table 22, and are attached at their bottom to a rod 30 25 looped at its centre to embrace the mast, but not connected with the latter. With this construction, when the mast is lowered from the position shown in Figure 1, to that shown in Figure 2, the rod 30 is lowered until it 30 rests on the top of the sleeve 5, and during the continued downward movement of the arms 29, which carry the baskets, the flexible body of the latter folds or collapses. When the mast is elevated, the baskets are also 35 lifted so that they are always in a position immediately below the arms 24. Again as the baskets are carried by the turn table, which also carries the bag detaching arms 24, it follows that when an arm is engaged 40 by the mail bag suspending rope or cable and turned rearwardly, the baskets turn with the arms and are therefore always in a position to receive the bag 27 when the latter becomes detached from its rope 26.

45 Secured to the yoke 15, between the side members thereof, is the cross head 31 of the lever 30. This cross head is journalled at its ends in the side members of the yoke, and the lever 30 which projects forwardly there- 50 from, as shown in Figure 1, is attached to one end of wire 32, the other end of said wire being secured to the pin 7 carried by the sleeve 5. This wire passes around sheave 33 on the jointed arm 17, and thence rear- 55 wardly over sheave 34 carried by the mast, and operates to hold the jointed arm in proper position when the mast is elevated, and to slack up and permit the joint 18 in arm 17 to break as the mast is lowered. As 60 the mast rises from the position shown in Figure 2, the slack on the wire 32 is taken up, and the pull thereof on the lever 30 causes the latter to fulcrum on the top of the mast and thus elevate the yoke and the rear 65 end of the frame 16 carried by the yoke,

while the pull of the wire on the jointed rod 17 straightens the latter thus elevating the front end of frame 16, so that by the time the mast reaches its normal operative position, the frame 16 will have been elevated 70 to a horizontal position above the top of the mast and so held by the tension of wire 32. In lowering the mast, the loosening up of the wire permits the joint in rod 17 to break and thus gradually lower the front end of frame 16, and as the descent of the mast continues, the springs 35 secured to the mast and acting on the pins 36 projecting from the yoke 15 at the sides of the bearing in the mast for the latter, throw the yoke rear- 75 wardly thus lowering the rear end of frame 16, the wire 32 in the mean time, permitting of the collapsing of these parts only as the mast descends and preventing any sudden dropping of any of the parts. 80

In the operation of the apparatus the mail bag 27 is suspended by cable 26 from an aeroplane flying sufficiently close to the apparatus for the pilot to readily see all parts of the latter, and accurately judge the elevation at which the bag 27 must hang. The bag must be in a horizontal plane below the arm 24, and above the bottom of the baskets and this space is therefore made ample so that great accuracy in positioning the bag 90 by the pilot will not be required. The pilot should move in the general direction of the pointed end of the frame 16 which can be turned by the wheel 8 and worm 9 to any direction, so as to bring the apex of the 100 guiding frame toward the approaching aeroplane or in the general direction to be traversed by the same. As the aeroplane approaches the station, the bag is lowered by an operator to a predetermined distance below the machine and the latter brought to the proper altitude by the pilot. As the aeroplane continues its flight the cable 26 engages one side of the guiding frame 16, along which it slides until it encounters one 110 of the arms 24 and enters one of the slots 25 in the latter. After the cable has entered the slot the continued pull on the cable draws it over the arm and pulls the bag holding means up into contact with the un- 115 derside of the arm, as shown in Figure 5.

The bag holding means comprises two jaws 36 pivoted together and adapted to embrace the sphere or ball 37 carried at the end of cable 26. Each jaw 36 is concaved and adapted to embrace the sphere as shown and each is provided with a depending finger 38, the two fingers being so positioned that the weight of the bag thereon holds the jaws 36 on the sphere. Each jaw is also provided 120 with an upwardly and outwardly projecting end 39a, adapted to engage the underside of the arm 24 so that when they are pulled into contact with the underside of the arm they will force the clamping jaw open and release 125 130

the bag, which is then in position to fall into one of the baskets, which latter, as previously explained is free to give or turn under the impact of loaded bag and thus prevent injurious contact.

The sphere 37 is considerably smaller than the width of the slots 25 in the arms 24, consequently after the holding jaws 36 have been disengaged from the sphere, the latter is free to be drawn through the slot without danger of wedging therein.

The cable 26 also carries the mail bag catcher 39, which is rounded or oblong; slightly concaved at its upper end and provided with a continuous series of sharp ridges externally throughout its length. This catcher is located so as to come between the turn table 22 and the guiding frame 16, as shown in Figure 1 and enter the looped 20 rope 40 to which the mail bag 27^a is secured. This bag 27^a which is to be taken up by the aeroplane is placed on the platform 20, and the loop 40 thereof is passed around the arms 41 carried by the platform which arms 25 extend out beyond the sides of the guiding frame 16, as shown in Figure 4. The loop 40 extends up to and over guiding frame 16 so that the catcher 39, which is guided in its movements by the guiding frame 16, will enter the loop. The catcher, when it strikes the loop, will engage it and pull it and the bag 27^a from the platform. As the catcher engages the loop 40, the upwardly projecting points formed by concaving its upper end 30 and grooving its sides, engage the loop and causes the opposite portion thereof on opposite sides of the catcher to enter the grooves in the latter and thus hold the loop against accidental detachment even under 40 the swaying action of the bag.

After one bag has been discharged and one bag caught, the apparatus may be lowered until time for the next delivery.

Having fully described my invention what 45 I claim as new and desire to secure by Letters-Patent, is:—

1. In an aeroplane mail delivering apparatus, the combination of a mast, means for raising and lowering the same, a guide carried by the mast and adapted to be turned toward the approaching mail bag, a receptacle for the mail bag located below the guide, and means intermediate the guide and the receptacle for detaching the mail bag 55 from its suspending means.

2. In mail bag delivering apparatus, the combination of a receiving receptacle for a mail bag, a diagonally disposed guide for directing a suspended mail bag laterally and into a position to enter the receiving receptacle, and means located in a horizontal plane intermediate said guide and the receptacle for releasing the bag from its suspending means.

3. In a mail bag delivering apparatus, the

combination of a receiving receptacle for a mail bag, the said receptacle being yieldingly mounted so as to give under impact, a diagonally disposed guide for directing a suspended mail bag laterally and into a position to enter the receiving receptacle and means for releasing the bag from its suspending means.

4. In an aeroplane mail delivering apparatus, the combination of a receiving receptacle, a V-shaped guide for directing a suspended bag to said receptacle, means for disconnecting the bag from the suspending means and a rotary mast carrying the receptacle, guide and bag disconnecting means.

5. In an aeroplane mail delivering apparatus, the combination of a support, a mail bag receiving receptacle mounted to move on said support, a guide for directing a suspended bag to the receptacle, and means also mounted to move on said support for disconnecting the bag from the suspending means; the said disconnecting means being connected with the means carrying the receptacle whereby they will be moved together 90 and in the same direction by the contact of the suspending means with the disconnecting means, or the contact of the mail bag with the receptacle.

6. In an aeroplane mail delivering apparatus, the combination of a rotary adjustable mast, a mail bag receiving receptacle carried on said mast and adapted to turn on the latter, a guide for directing a suspended mail bag to said receptacle, and means for disconnecting the bag from the suspending means, the said disconnecting means being also movably mounted on the mast.

7. In an aeroplane mail delivering apparatus, the combination of a rotary adjustable mast, two baskets carried by the mast, a guide for guiding a suspended mail bag to either of said baskets, and means for disconnecting the bag from the suspending means.

8. The combination of a mast, means for elevating and lowering it, means for turning it, basket supporting means mounted to turn on said mast, two baskets carried by said supporting means, a guide for directing a suspended bag to either of said baskets, and means for disconnecting the bag from the suspending means.

9. The combination of a rotary and vertically movable mast, basket supporting means mounted to turn on said mast, two baskets carried by said supporting means, a guide for directing a suspended bag to either of said baskets and means for disconnecting the bag from the suspending means.

10. The combination of a mast, a V-shaped guide carried by said mast and adapted to be raised and lowered thereon, mail bag receiving means also carried by said mast, and means intermediate the guide and receiving

means for disconnecting the bag from the suspending means.

11. The combination of a mast, means for raising and lowering and turning the same, 5 a guide carried by the mast at the upper end of the latter, a receiving basket and means intermediate the receiving basket and guide, when the latter is in its elevated operative position for disconnecting the bag 10 from its suspending means.

12. In a mail bag delivering apparatus, the combination of a support, an arm carried by said support and having curved slots 15 therein, a basket at the rear of the arm, a suspending device terminating in a holding member, and a clamp carrying a mail bag and composed of two jaws adapted to embrace 20 said holding member on the suspending device, each jaw of the clamp having an upwardly projecting end or lug adapted to engage the under side of the slotted arm whereby when the lugs on the

clamp engage the arm, the jaws will be forced apart thus releasing the bag from the suspending means.

25

13. In a mail bag delivering and receiving apparatus, the combination of a support, a basket for receiving a bag of mail, a platform for supporting a bag of mail, the said bag having a loop to be engaged by a 30 catching device, a guide for guiding a mail bag suspending device, means for detaching the bag from said suspending device, and a catching device carried on the suspending device and adapted to engage the loop on 35 the bag carried on the platform of the support.

In testimony whereof, I have signed this specification in the presence of two subscribing witnesses.
